UNITED STATES PATENT OFFICE.

AUGUSTUS L. CLARK, OF MONTPELIER, VERMONT.

DOMESTIC GAS PLANT.

Application filed November 9, 1926. Serial No. 147,354.

The object of my invention is to provide a domestic gas plant of relatively simple and inexpensive construction which does not require a large plant for its operation but which is of suitable size to permit of its use by individual householders and which is capable of manual operation. It is an especial object of my invention to eliminate some of the mechanism required in prior plants in this art.

I attain the different and other objects of my invention by the mechanism illustrated in the accompanying sheet of drawing, showing a perspective view of the apparatus.

Referring to the accompanying drawing, I provide a small domestic heating apparatus 1 of any suitable size, the one illustrated being 2½ ft. by 3½ ft. by 2 ft. one of the principal purposes of this invention being 20 to provide an efficient apparatus of relatively small size as shown in the drawing. I provide a gasifying retort 2, a mouthpiece or damper 4 and a door or lid 3 on top through which the charcoal or coke is supplied to 25 heat the retort. The retort is made in two sections, an upper section and a lower section which are bolted together in addition to which there is an air-tight door. I provide a pipe 5 leading from the retort to a 30 hydraulic tank 7. Tank 7 is a small tank about two-thirds full of water, the water level being indicated in the drawing by a dotted line. Pipe 5 extends into hydraulic tank 7 to a point three-fourths of an inch 35 below the water level. I provide a manually operated valve 6 in pipe 5. Opening out of hydraulic tank 7 is a pipe 8, provided with a pressure gauge 9, leading to a gas exhauster 11 which may be a manually operated gas exhauster. I provide a valve 10 in 40 pipe 8 in proximity to the gas exhauster 11. I provide a pipe 12 leading from gas exhauster 11 into the gas holder 13 and terminating in a plane above the water level 45 14 in said tank. The gas holder 13 consists of a stationary tank section 13 and a telescopic inverted top section 15, provided with a plurality of guide arms 16 which extend downward outside of the walls of tank 13, 50 in slidable contact therewith and functioning also as weight elements for the telescopic section. The telescoping section 15 is approximately similar in length to stationary section 13 so that inside section 15 will still 55 extend to a plane below the water level 14 when the holder is well filled with gas. I

provide pipe 17 opening out of holder 13 and leading to a gas purifier 18 out of which an outlet pipe 19 leads to deliver the gas to parts of the house where it is to be used.

In operating the plant charcoal or coke may be used in the furnace for heating the retort. The first step is to heat the retort to a cherry red heat before putting in the fuel to make gas. The fuel for making gas 60 may be soft coal or wood which is placed in the retort 2 after the retort is hot. The door of this retort is air-tight and after the fuel has been placed in the retort the operator turns the handle which drives the gas 65 exhauster 11, at the same time observing the pressure gauge 9 to see how fast to operate it. For the purpose of making gas I may, however, use any waste grease or old oil available as it can be successfully made into gas 70 for heating and lighting purposes. For this purpose waste automobile oil can be put into a piece of gas pipe with a cap on one end of the pipe and the other end open. A piece of waste may be stuffed into the open end of the pipe after being filled with the oil. The pipe of oil is then placed in the retort with the end containing the waste adjacent the rear end of the retort 2 so that the waste 75 will burn out and the oil will be gasified as 80 it comes to the front of the standpipe 5. Oil for making gas may be admitted with the coal or wood used as a fuel, also for making gas in the retort. Thus I distill coal or 85 wood and waste oil, making thereby a mixture of combustible gases as well as producing coke or charcoal in the retort tube.

The gas flows through pipe 5 into the hydraulic tank 7 being released below the level of the water in that tank to purify the 90 gas. From that tank it is drawn through pipe 8 by operation of the gas exhauster 11 and conveyed through pipe 12 into the telescopic gas holder 13 where it may be collected for future use as required. Pipe 17 95 which extends into the gas holder to a point above the water level 14 conveys the gas from the gas holder to the purifier box 18 and from purifier box 18 through pipe 19 to the various parts of the house where it is 100 to be used for heating or lighting purposes.

After a desired quantity of gas has been produced by gasifying the waste oil in the manner already described the valves 6 and 10 are closed and the coke or charcoal is 110 removed from the distillation retort 2. It will be understood that the telescopic

gas holder 13 may be made as large as desired, the larger it is made the greater the amount of gas that may be stored. The plant is capable of being operated with a comparatively small amount of relatively inexpensive material.

What I claim is—

1. In a domestic gas plant capable of manual operation, the combination of a small domestic heating apparatus, a distillation retort heated thereby and adapted to receive material from which the gas is to be produced, a small hydraulic tank, a valve-controlled pipe leading from the retort into the hydraulic tank below the water level of said tank, a manually operated gas exhauster, a valve-controlled conduit leading from the hydraulic tank to the gas exhauster, a gas holder, a conduit leading from the gas exhauster to the gas holder, an outlet pipe leading from the gas holder, a purifier box into which said pipe leads, the gas holder having a telescopic inverted top section, said top section having a plurality 25 of arms affixed to the outer walls of the top

section and engaging over the outer wall of the lower stationary section to suitably and telescopically engage the top section in operative relation to the bottom section.

2. A domestic gas plant capable of manual operation, having in combination, a domestic heating apparatus, means for feeding said heating apparatus from the top thereof, a retort mounted directly on and heated by said heating apparatus said retort having a door, a hydraulic tank, a valve-controlled pipe from the retort to the hydraulic tank and terminating at a point below the water level of said tank, a gas exhauster, a manually operated valve controlled conduit 40 from the hydraulic tank to the gas exhauster, a telescopic gas holder having a telescoping section provided with guide arms of nearly equal length to the aforesaid telescoping section, a conduit from the gas exhauster to the gas holder, an outlet pipe from the gas holder, a purifier box with which said outlet pipe communicates, and a gas outlet pipe from the purifier box.

AUGUSTUS L. CLARK.
